[57] **CLAIM**

The ornamental design for a combined bathtub faucet and hand shower, as shown and described.

DESCRIPTION

FIG. 1 is a front elevational view of a combined bathtub faucet and hand shower showing my new design;
FIG. 2 is a left side elevational view thereof;
FIG. 3 is a rear elevational view thereof;
FIG. 4 is a top plan view thereof; and
FIG. 5 is a bottom view thereof.

The flexible hose is shown as broken away in FIGS. 1, 3, 4 and 5 for convenience of illustration only.
